US00D927262S

(12) **United States Design Patent** (10) Patent No.: **US D927,262 S**
(45) Date of Patent: **** Aug. 10, 2021**

(54) **BACKPACK COOLER**

(71) Applicant: **YETI Coolers, LLC**, Austin, TX (US)

(72) Inventors: **Jeffrey Charles Munie**, Austin, TX (US); **Kyle Edward Rogers**, Austin, TX (US); **Donald Edward Desroches**, Austin, TX (US); **John Loudenslager**, Austin, TX (US); **Derek G. Sullivan**, Austin, TX (US); **Alex Baires**, Austin, TX (US)

(73) Assignee: **YETI Coolers, LLC**, Austin, TX (US)

(**) Term: **15 Years**

(21) Appl. No.: **29/765,057**

(22) Filed: **Jan. 5, 2021**
